UNITED STATES PATENT OFFICE.

PETER BROADBOOKS, OF BATAVIA, NEW YORK.

QUICK-SLIDING BENCH-VISE.

No. 851,397.

Specification of Letters Patent.

Patented April 23, 1907.

Application filed November 13, 1905. Serial No. 287,011.

To all whom it may concern:

Be it known that I, PETER BROADBOOKS, a citizen of the United States, residing at Batavia, county of Genesee, and State of New York, have invented a certain new and useful Improvement in Quick-Sliding Bench-Vises, of which the following is a specification.

My invention relates to a new and useful improvement in quick sliding bench vises, and has for its object to provide such a vise, the sliding jaw of which may be quickly moved back and forth in clamping and unclamping work and when adjusted to any particular point just prior to tightly clamping said work, the sliding jaw will be firmly locked, and yet when the work is unclamped this jaw may be slid to and fro throughout its full movement without the manipulation of any levers or locks.

Another object of my invention is to provide a vise with two friction plates and a screw which shall have a large bearing surface between the head and the collar so as to lessen the friction thereof.

With this end in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawing forming a part of this specification, in which—

Figure 1 is a side elevation of the vise made in accordance with my improvement, a portion of the body thereof being broken away so as to clearly show the beveled surface, the meeting of which with the straight surface of the bottom of the guide-way forms one of the locking points for the tail block or slide. Fig. 2, the bottom view of the front jaw showing the safety screw for limiting the movement of said jaw relative to the tail block. Fig. 3, a section of the tail block showing the body, a stationary jaw in front elevation. Fig. 4, a front view of the vise, the operating screw being in section, and Fig. 5, a cross section of a tail block having a single groove formed therein instead of two grooves as shown in Fig. 3.

In carrying out my invention as here embodied, A represents the body of the vise with which is formed the stationary jaw A',

said body being provided with the ordinary flanges B by which it may be bolted to the bench or any suitable object, and the body has formed therethrough a rectangular opening C as is usual in bench vises, this opening serving as a guide for the tail block adapted to slide therethrough.

Formed with the sides of the body A are the bosses E through which are threaded the bolts F, the inner ends of said bolts being flat for the purpose as hereinafter set forth.

The tail block D has formed therein the grooves G which run the full length of said block and the lower wall of each of these grooves is at the same angle as the flat end of the bolt F adapted to bear thereon as clearly shown in Fig. 3, the opening C through which the tail block is adapted to slide has its bottom wall beveled or cut away as indicated at H, and where this cut-away surface meets the straight surface of the bottom wall, an edge or line I is formed so that by proper adjustment of the bolts F said line and bolts will serve as clamping points by which the tail block will be firmly locked when pressure is put upon the tail block to draw it upward.

J is the sliding jaw the body of which is fitted upon the forward end of the tail block D so as to slide thereon, and a screw K is threaded into the tail block and provided with the collar L and the head M, through which the operating lever N passes in the usual manner.

The operating screw K being reduced to a smaller diameter between the head and the collar gives a larger bearing surface at the point and is held in its relative position to the movable jaw by the friction plates O and P which are screwed in place by the screws Q.

In practice the operation of my improved vise will be as follows:—To open the vise the sliding jaw is slightly raised so as to carry the tail block out of contact with the bolts F when it may be drawn forward any distance for placing the work between the jaws and by moving it backward until the sliding jaw is in contact with the work and lowering it sufficiently to cause the tail block to again come in contact with the bolts the tail block will be firmly locked against any further movement after which it is only necessary to manipulate the lever N to revolve the screw in the proper direction to force the sliding jaw tightly against the work, and the mere force put upon the sliding jaw by the screw the tighter will be the grip upon the tail

block, it being obvious that the tail block acts as a lever, a fulcrum being at the line I, the power being represented by the force which the sliding jaw bears upon the work, this 5 force having a tendency to press the forward end of the tail block downward thereby forcing the lower walls of the grooves G firmly against the bolts F. From which it will be seen that the locking of the tail block in any 10 adjustment does not depend upon friction but upon the cramping action given to the tail block when the sliding jaw is forced in contact with the work. To release the work it is only necessary to turn the screw back- 15 ward a short distance when the pressure will be removed from the work sufficiently to permit the forward end of the tail block to be elevated which will free it from contact with the bolts F and permit it and the sliding jaw to be drawn upon to any extent.

While in my improved vise work may be quickly clamped and unclamped and as firmly held as in the ordinary form of bench vise, and this clamping and unclamping requires 25 the use of only one hand of the operator leaving the other hand free to manipulate the work thereby saving considerable time in the operation of the vise.

The large diameter of the collar L and the 30 head M gives an increased bearing surface upon the plates O and P, thus providing a substantial construction at this point.

For small vises and those not intended to handle heavy work the tail block D may 35 have only one groove as indicated at G in Fig. 5.

Any wear which takes place upon the bottom surface of the tail block or the lower walls of the grooves G is readily compensated 40 for by setting up the bolts F.

A screw U is utilized to limit the movements of the sliding jaw J relative to the tail block D thus preventing the operator from backing off the screw K to too great an extent. A block S is secured to the sliding jaw 45 J to increase its bearing.

Having thus fully described my invention, what I claim as new and useful is,—

1. In a vise of the character described, a 50 body, said body having an opening therethrough, a portion of the bottom wall of said opening being cut away or inclined, a tail block adapted to slide through said opening and be tipped therein, said tail block having 55 a groove formed upon its side, a bolt threaded into the body so that its lower end will bear upon the lower wall of said groove whereby the tail block will be locked in any adjustment when in its normally horizontal 60 position and a sliding jaw fitted upon one end of the tail block, as and for the purpose set forth.

2. In a vise of the character described, a 65 body, a tail block adapted to slide there- through, an angle attached or formed upon

the bottom wall of the opening through which the tail block slides, a bolt threaded through this body, the lower end of which is adapted to bear against an inclined surface formed upon the tail block, a movable 70 jaw fitted to slide upon the forward end of the tail block, a screw for operating said jaw whereby pressure may be brought to bear upon the work placed between the jaws of the vises, and thus firmly locking the tail block 75 in its adjustment, as specified.

3. The herein described combination of a body, a stationary jaw formed therewith, a tail block adapted to slide through the body and having bevelled surfaces formed thereon, an angle formed upon the bottom wall of the opening in the body through which the tail block slides, bolts threaded through the body and adapted to bear against said bevelled surfaces, a movable jaw fitted to slide 85 upon the forward end of the tail block, a screw journaled in the movable jaw and threaded into the tail block and means for revolving said screw, as and for the purpose set forth.

4. In a vise of the character described, a 90 body having an opening formed therethrough for the passage of the tail block, an angle attached or formed upon the lower wall of said opening by said wall being made in two planes, and a bolt threaded through the 95 body, its lower end adapted to bear upon the tail block when the latter is in its locked position whereby said tail block will act as a lever, the fulcrum of which will be the angle I so that when work is clamped in the vise this tail block will be forced upward against the 100 bolt, as specified.

5. In a vise of the character described, a body, a stationary jaw formed therewith, a tail block adapted to slide through the body, 105 bolts threaded through said body and adapted to bear upon the tail block when the latter is in a locked position, a movable jaw adapted to slide upon the forward end of the tail block, a block S attached to the movable 110 jaw, a screw K threaded into the tail block, a collar L formed upon the screw and head M also formed upon the screw, plates O and P secured to the movable jaw between the collar and the head M so as to hold the screw in 115 place, and a stop screw R for limiting the movement of the movable jaw relative to the tail block, as and for the purpose set forth.

6. In a vise of the character described, the combination of a body having an opening therethrough for the tail-stock and an angle in the bottom of the opening adapted to serve as a fulcrum and biting point for the tail-stock and upon which the tail-stock may be locked, a smooth-surfaced tail-stock slidably fitted in said opening and resting upon said angle, an adjustable locking device set in the body above and in rear of the angle and adapted to engage the tail-stock when the latter is brought to its normal, substantially 125 130

horizontal, position and to act in conjunction with the angle to automatically lock the tail-stock, and a jaw on the forward end of the tail-stock adapted to keep it in normally locked position, substantially as described.

7. In a vise, the combination of a body having an opening therethrough for the passage of the tail-stock, the bottom wall of said opening having an angle constituting a biting fulcrum for the tail-stock,—a smooth surfaced tail-stock adapted to slide through said opening and be tipped therein when being adjusted, an adjustable device set in the body above the angle and adapted to bear upon the tail-stock in rear of the angle; whereby the stock will be automatically locked in any adjustment when its outer end is lowered to substantially horizontal position, and a jaw on the outer end of the tail-stock.
8. In a vise, the combination of a body having an opening therethrough for the passage of the tail-stock, the bottom wall of said opening having an angle constituting a biting fulcrum for the smooth surfaced tail-stock, a tail-stock adapted to slide through said opening, a bolt adjustably set in the body above and in rear of the angle and adapted to have its inner end bear upon the tail-stock in rear of the angle whereby the stock will be automatically locked when its outer end is lowered to substantially horizontal position, and a jaw attached to the outer end of the tail-stock.

9. In a vise of the character described, the combination of a body having an opening therethrough for the tail-stock and an angle adapted to serve as a fulcrum or biting point upon which the tail-stock may be locked, a smooth surfaced tail-stock slidably fitted in said opening, an adjustable bolt set in the body above and in rear of the angle and adapted to engage the tail-stock and act, in conjunction with the angle to automatically lock the tail-stock in any adjusted position when the latter is brought to its normal, substantially horizontal, position, a movable jaw mounted to slide upon the forward end of the tail-stock, and means for operating said movable jaw, for the purpose set forth.

10. In a vise of the character described, the combination of a body having an opening therethrough for the tail-stock and an angle in the bottom of the opening adapted to serve as a fulcrum or biting point upon which the tail-stock may be locked, a tail-stock slidably fitted in said opening and having an inclined bearing surface on its side; an ad-

justable locking device set in the body above and in rear of the angle therein and adapted to engage the inclined bearing surface of the tail-stock to act in conjunction with the angle in the bottom to lock the tail-stock, and a jaw on the forward end of the tail-stock, for the purpose set forth.

11. In a vise, the combination of a body having an opening therethrough for the passage of the tail-stock, the bottom wall of said opening having an angle constituting a biting fulcrum for the tail-stock,—a tail-stock adapted to slide through said opening and be tipped therein when being adjusted and having oppositely inclined bearing surfaces on its sides; bolts adjustably set at an angle in the body and adapted to have their inner ends bear upon the inclined bearing surfaces of the tail-stock in rear of the angle; and a jaw on the outer end of the tail-stock.

12. In a vise, the combination of a body having an opening therethrough for the passage of the tail-stock, the bottom wall of said opening being provided with a biting fulcrum for the tail-stock, and a tail-stock adapted to slide through said opening and having an inclined bearing surface on its side; a bolt adjustably set at an angle in the body above and in rear of the fulcrum and adapted to have its inner end bear perpendicularly upon the inclined bearing surfaces of the tail-stock in rear of the fulcrum whereby the stock will be locked when its outer end is lowered to substantially horizontal position, and a jaw attached to the outer end of the tail-stock.

13. In a vise of the character described, the combination of a body having an opening therethrough for the tail-stock and a fulcrum or biting point upon which the tail-stock may be locked, a tail-stock slidably fitted in said opening having oppositely inclined bearing surfaces on its opposite sides, oppositely inclined bolts set in the body above and in rear of the fulcrum and adapted to engage the opposite bearing surfaces of the tail-stock and act, in conjunction with the fulcrum to lock the tail-stock in any adjusted position, and a jaw mounted upon the forward end of the tail-stock, for the purpose set forth.

In testimony whereof, I have hereunto affixed my signature in the presence of two subscribing witnesses.
